UNITED STATES PATENT OFFICE.

ROBERT HEAD, OF NEW YORK, N. Y., ASSIGNOR TO JAMES T. OUTERSON, OF NEW YORK, N. Y.

LIGHTING SYSTEM FOR MOTOR-VEHICLES.

1,157,105.

Specification of Letters Patent. Patented Oct. 19, 1915.

Application filed November 8, 1910. Serial No. 591,224.

To all whom it may concern:

Be it known that I, ROBERT HEAD, a citizen of the United States, residing in the city of New York, borough of Manhattan, county and State of New York, have invented a certain new and useful Lighting System for Motor-Vehicles, of which the following is a specification.

This invention is a lighting system, the same being intended for use on vehicles of all kinds, and more particularly on motor vehicles, although the system, or parts thereof, may be used for illuminating purposes generally.

15 I will hereafter describe my invention as adapted for lighting one or more head lights of a motor vehicle, marine craft, etc., but it is manifest that the system may be adapted for lighting the tail lights or the side lights, 20 or all the lights used for signaling and illuminating purposes on the vehicle.

25 My system embodies distinctly novel features for controlling the flow of an illuminating gas to the lamp or lamps, and in the generation of an electric spark at the point of ignition at the said lamp or lamps, whereby the gas is first turned on and immediately thereafter the ignition spark is established for the purpose of lighting one or more 30 lamps in the illuminating circuit.

In a preferred form, the means for establishing the flow of gas, and the means for controlling the production of the ignition spark, are both operated by a manually operated member common to the aforesaid devices. Said manually operated member is adapted by movement in one direction to open the gas flow and to establish the ignition spark, but a movement of said member 40 in a reverse direction cuts off the gas flow and breaks the circuit generating the spark. Furthermore, the manually operated member acts to first turn on the gas flow and after the lapse of an appreciable interval of 45 time, to establish the ignition spark, whereby the gas will be permitted to flow to the burner or burners by the time the spark is generated, whereby a gas valve and an electric switch will be operated successively and 50 in due order.

It is desirable to preclude tampering with the lighting apparatus, as when a chauffeur is not in attendance upon a motor vehicle equipped with the invention. To this end,

the manually operated member is embodied 55 in the form of a wrench or key adapted to be removed from operative relation to the parts coöperating therewith.

Other features of the invention will appear in the course of the annexed detailed 60 description.

In the accompanying drawings I have illustrated one practical embodiment of the invention, but the construction shown therein is to be understood as illustrative, only, 65 and not as defining the limits of the invention.

Figure 1 is a diagrammatic view illustrating the invention adapted for use on motor vehicles and illustrating a plurality of head-lights in the lighting system. Fig. 2 is a vertical sectional view through one of the headlights, illustrating a gas burner and the lighting terminals of an electric circuit in coöperation to said gas burner. Fig. 3 is 75 an enlarged detail view of a burner equipped with a part of the invention and adapted for attachment to an ordinary lamp. Fig. 4 is a plan view of the burner shown in Figs. 2 and 3. Fig. 5 is an enlarged view in vertical section, illustrating 80 one embodiment of a valved gas fitting and an electric circuit controller or switch mechanism adapted for operation by a single device. Fig. 6 is a front view of the device 85 shown in Fig. 5. Figs. 7 and 8 are plan views of the device shown in Figs. 5 and 6, illustrating two positions of the circuit controlling or switching mechanism. Fig. 9 is a detailed view of the gas fitting shown in 90 Figs. 5 and 6 with the electrical appliances disconnected therefrom. Fig. 10 is a perspective view of the wrench or key adapted for use in connection with the circuit controlling or switch mechanism of Figs. 5 to 95 8, inclusive.

Referring to diagram, Fig. 1, A, B, designate a plurality of lamps. C, are gas burners positioned within said lamps, and are supplied with gas from a generator or tank, 100 D, by pipes, d, d', d'', d''. The pipes d, d', are connected with a valve fitting, E, provided with two valves E', E'', the valve E' being operated by a removable key or wrench, F, for the purpose of establishing 105 or cutting off the flow of gas to the burners, but valve E'' is operated independently of valve E' in order to regulate the volume of

gas which flows through the fitting to the burners. Each burner is equipped with terminals g , g' , of a lighting circuit, G , said lighting circuit including batteries, h , and 5 a spark coil, h' , and a switch mechanism indicated in its entirety by the reference character, I . This switch mechanism includes two contacts, i , i' , shown more clearly in Figs. 7 and 8 and the moving contact j , said 10 moving contact being under the control of key or wrench, F , so that when valve, E' , is turned to an opened position the moving contact, j , will bridge between contacts, i , i' , and operate to close the electric circuit in 15 order to produce jump sparks at the terminals, g , g' , of the light circuit whereby the gas issuing from burners, C , will be ignited automatically. I will now proceed to describe in detail the several parts of the lighting system.

Each lamp, A or B , is of ordinary construction, the same being provided with ventilating openings in a hood, a' , a reflector, b , at the rear of the lamp and a glass 25 pane, b' , at the front of the lamp, but the detailed construction of the lamp may be varied within wide limits, and according to the style or type of lamp used in the light circuit.

30 When the system is used in conjunction with the head lights on an automobile, the lamps should be provided with reflectors, but these reflectors are not necessary ordinarily when using the light system in conjunction with the side or tail lights of automobiles.

It is preferred to employ a burner, C , of the form illustrated more particularly in Figs. 3 and 4. As shown, the burner comprises 40 a tube adapted to be secured upon a nipple, c , which is attached to the base of the lamp in a manner to communicate with one of the two branch pipes, d^2 or d^3 . The burner tube is composed of metal in order 45 to serve as an electrical conductor as well as a gas conduit, such tube being provided at its upper part with a burner tip, C' . Ordinarily acetylene gas is employed for lighting the headlights of an automobile, and the 50 tip shown in Figs. 3 and 4 is provided with two orifices or gas outlets, c' , whereby gas will issue in jets to impinge against each other in a well known manner.

One lighting terminal, as g' , is rigidly 55 fastened in any suitable way to the tube of burner, C , in a manner to be supported mechanically by said burner tube and to be in electrical contact therewith. The other terminal, g , is attached rigidly to a sleeve, g^2 , which is fitted on the burner tube and is insulated electrically therefrom, at g^3 . With 60 this sleeve, g^2 , engages a spring contact, g^4 , the latter having a bent lower end, k , which is insulated at k' from the base of the lamp, 65 such insulated contact being fastened to the

base of the lamp by a binding post, k^2 . The lower end of the burner tube engages electrically with another contact, l which is insulated at l' from the base of the lamp, said contact being fastened in position by a binding post l^2 .

The terminals, g , g' , of the lighting circuit associated with each burner are positioned to lie close to the gas jets issuing from the orifices of tip, C' , whereby an electrical 75 spark which jumps from one terminal to the other will operate to ignite the gas and produce the required light. As shown in the diagram, Fig. 1, a conductor, m , of lighting circuit, G , leads from battery, h , to binding 80 post, k^2 , of lamp, A , so that the current will pass through contact, g^4 , sleeve, g^2 , and terminals, g , the spark jumping across to the other terminals, g' , and the current passing through the tube or burner, C , to contact, l , 85 and binding post, l^2 . From binding post, l^2 , runs a conductor, m' , which is shown as extending to a binding post, l^2 , of lamp, C , so that the current will flow through contact l , the tube or burner, C , positioned in lamp, 90 B , thence through terminal, g' , across to terminal, g , thence through sleeve, g^2 , contact g^4 and binding post, k^2 of said lamp, B . From the binding post, k^2 , of lamp, B , runs a conductor, m^2 , which is shown as extending 95 to switch contact, i' . Conductor, m , leads from the battery to spark coil, h' , and thence to the other switch contact, i , whereby the circuit will be completed when the moving switch contact, j , bridges the space 100 between switch contact, i , i' . The tank or generator, D , may be of any suitable character. If acetylene gas is to be employed as the lighting medium I provide a generator 105 of one well known form or another, but it is not intended to limit the invention to the employment of an acetylene gas generator, for the reason that any other type of generator may be used and I may, also, employ 110 a tank for holding gas under pressure. From the tank or generator, D , extends a pipe, d , the same being connected with a fitting, E .

In one form of the invention I employ a fitting adapted to be attached to the dash board of an automobile, but it is not desired to limit the invention to use in connection with this particular type of fitting, for the reason that other constructions may be employed for controlling the flow of gas from the generator or tank to the burners. As shown, fitting, E , comprises two horizontal members or legs, e , e' , and a vertical member or leg, e^2 , said vertical member connecting the horizontal members. The horizontal members are provided with collars, e^3 and with nuts, e^4 , whereby members, e , e' , are adapted to be inserted through apertures of the dash board, O , so that collars, e^3 , and nuts, e^4 , will coöperate with the dash board 115 120 125 130 135

in clamping the fitting in a fixed position thereon. Member, e , of the fitting is provided with a stuffing box, p , in which works needle valve, E^2 , adapted to be adjusted for regulating the flow of the volume of gas to be applied to the burners. The vertical member of said fitting is provided with a valve seat, p' , and with a stuffing box, p^2 , said valve seat accommodating needle valve, E' , which passes through the stuffing box. Said needle valve is adapted to be adjusted for cutting off the flow of gas through the fitting, or for establishing the flow of gas from the generator to pipe, d' , the latter being attached to member, e' , of the fitting, whereby gas will flow through branches, d^2 , d^3 , to the burners within lamps, A. B.

Valve, E' , is shown as extending a suitable distance above the vertical member of the fitting, said valve having a square or polygonal extremity, q . Key or wrench, F , is provided with a square or polygonal aperture, f , for the purpose of engaging with the correspondingly shaped end, q , of valve, E' , whereby the key or wrench is adapted to be placed in positive position upon the valve for the purpose of opening or closing it, and at the same time said key or wrench may be readily disconnected from the valve in order that persons other than the chauffeur may not tamper with said valve.

The switch mechanism which controls the electric circuit may be of any suitable construction, but, as shown herein, said switch mechanism includes a rotatable member, Q . Said member is in the form of a disk fitted loosely upon a cylindrical protruding part of valve, E' , whereby the disk is free to turn independently of the valve. The disk is provided with a moving switch contact, j , the latter being insulated electrically at, j' . Furthermore, the disk is provided with a member, q' , adapted to lie in the path of a shoulder or lug, f' , of the key or wrench, whereby said key or wrench is adapted to coöperate with disk, Q , for the purpose of turning the disk when the gas valve is opened. The rotatable disk is under the action of a retractor, herein shown as a spring, R , said spring being mounted loosely upon the protruding end of valve, E' . The spring is provided with two arms, r , r' , the former engaging with the plate, R' , forming a part of fitting, E , while the other arm, r' , engages with, or is attached to, disk, Q . The spring acts on the disk to turn it normally into position of Fig. 7 for the purpose of retaining the movable switch contact, j , out of engagement with both stationary switch contacts, as i , i' , but when the key or wrench is in position for its lug, f' , to engage with member, q' , on the disk, a movement of said key or wrench from the dotted line position of Fig. 7 to the dotted

line position of Fig. 8 will operate member, q' , to rotate disk, Q , thereby causing contact, j , to engage with both contacts, i , i' , for closing the electric circuit and establishing the electric sparks at the burners of 70 the lamps.

Fitting, E , is provided with plate, R' , for the purpose of supporting stationary switch contacts i , i' , in proper relation to the moving switch contact, j , said switch contacts, i , i' , being insulated at s from plate R' and said switch contacts being fixed in position on said plate by binding posts, s' , the latter operating to secure contacts, i , i' , and conductors, m , m^2 , in stationary positions 80 upon the plate and the gas valve fitting.

In Fig. 9 I have shown the gas valve fitting independently of the electrical switch mechanism, plate R' being disconnected from said valve fitting.

The operation of the invention will be apparent from the foregoing description, but may be summarized briefly as follows: The gas under pressure is stored in tank or generator, D , and valve E' is closed to cut 90 off any flow of gas from the tank or generators to the burners. Valve, E^2 , is adjusted to regulate the flow of the volume of gas, and said valve is permitted to remain at rest after such adjustment. For lighting 95 the lamps, the operator simply applies the key or wrench to valve, E' , and moves said key or wrench through an arc of a circle from the dotted line position in Fig. 7 to that of Fig. 8. Upon the application of 100 the key to the polygonal end of valve E' , lug, f' , of said key engages with member, q' of the disk, Q . The movement of the wrench opens valve, E' , and turns disk, Q , for contact, j , to engage with both contacts, i , i' . It will be seen that gas is permitted 105 to flow to the burners of the lamps by opening valve, E' , and immediately thereafter the electric circuit is closed by contact, j , bridging contacts, i , i' , whereby the battery and spark coil operate to produce jump 110 sparks at the plurality of burners. The gas is thus first turned on and the jump sparks immediately produced thereafter for the purpose of automatically lighting all the 115 burners immediately following the flow of gas to said burners, whereby the gas is lighted without appreciable loss. Furthermore, a plurality of lamps are lighted from mechanism positioned on the dash board 120 and under control of the chauffeur, thus relieving the chauffeur from the necessity of leaving his station to light the lamps. When the key or wrench is removed from valve, E' , spring, R , acts to return disk, Q , 125 and contact, j , to normal positions, thus extinguishing the lighting circuit and precluding waste of electrical energy after the lamps shall have been lighted.

It will be observed that burner, C , of 130

each lamp carries the electric lighting terminals in operative relation to the gas outlet, and that said burner coöperates with two circuit contacts which are positioned 5 within the lamp. Said burner may easily be removed from the lamp without disturbing the circuit contacts, whereby a wornout or clogged burner may be dismounted and a fresh burner substituted therefor without 10 requiring any special skill on the part of the operator.

In describing one embodiment of the invention the lamps and burners are shown as included in series in the electric circuit, 15 that is to say, the current passes between the terminals of one burner and thence to the terminals of the next burner, but it is not desired to limit the invention to this specific organization of the circuit to the burners 20 therein for the reason that the burners may be supplied with electric energy separately.

Having thus fully described the invention, what I claim as new, and desire to secure by Letters Patent, is:

- 25 1. In a device of the class described, the combination of a casing provided with a duct, a valve having a threaded stem co-operating with said duct for the purpose of allowing or precluding the passage of material through said duct, an electric circuit having a pair of spaced contacts positioned adjacent the valve stem, circuit closing means positioned adjacent the spaced contacts and mounted on the valve stem, a tension member normally retaining the circuit closing means out of engagement with the contacts, and valve operating means detachably mounted on the valve stem, and adapted for engagement with the circuit closing 30 means, whereby the actuation of the valve operating means, operates the valve to allow the passage of material through the duct, and simultaneously brings the circuit closing mechanism into engagement with the spaced contacts, such valve operating means being thereafter adapted to be removed from the valve stem whereupon the tension member is adapted to return the circuit closing 35 means to its initial position.
- 40 2. In a device of the class described, the combination of a casing provided with a duct, a valve having a threaded stem co-operating with said duct for the purpose of allowing or precluding the passage of material through said duct, an electric circuit having a pair of spaced contacts positioned adjacent the valve stem, circuit closing means loosely mounted on the valve stem, a tension member normally retaining the circuit closing 45 means out of engagement with the contacts, and valve operating means detachably mounted on the valve stem, and adapted for engagement with the circuit closing means, whereby the actuation of the

valve operating means, operates the valve to 65 allow the passage of material through the duct, and simultaneously brings the circuit closing mechanism into engagement with the spaced contacts, such valve operating means being thereafter adapted to be removed from 70 the valve stem whereupon the tension member is adapted to return the circuit closing means to its initial position.

3. In a device of the class described, a casing having a passage therein, inlet and outlet ducts communicating with said passage, a threaded needle valve extending into the passage of the casing and adapted to co-operate with a valve seat intermediate the inlet and outlet ducts for the purpose of 80 governing the flow of material through the latter, and means for actuating said needle valve, in combination with an electric circuit having spaced contacts exterior of the casing, a rotatable member loosely mounted 85 on the stem of the needle valve and provided with a conducting portion adapted to engage with the contacts of the electric circuit for the purpose of completing the same, means for normally maintaining the rotatable 90 member in its inoperative position, and co-operating means on the rotatable member and on the valve operating means for moving the former into a position to complete the circuit when the latter is operated to 95 allow of the passage of material through the outlet of the casing.

4. In a device of the class described, a casing provided with a duct, and a needle valve projecting into said duct for governing the 100 flow of gas therethrough, said needle valve having a stem extending exteriorly of the casing, in combination with an electric circuit having spaced contacts, a rotatable, circuit closing member co-operating with said 105 contacts, a spring for normally maintaining the circuit open, means detachably mounted on the valve stem for operating the valve, and co-operating means mounted on the circuit closing member and on the valve operating means for actuating the former to close the circuit against the tension of the spring when the latter is operated to open the valve, said spring being operable to return the circuit closer to its normally open 115 position, upon the removal of the valve operating means from the valve stem.

5. In a device of the class described, a casing provided with a duct, and a needle valve projecting into said duct for governing the 120 flow of gas therethrough, said needle valve having a stem extending exteriorly of the casing, in combination with an electric circuit having spaced contacts, circuit closing mechanism co-operating therewith, a spring 125 for normally maintaining the circuit closing member in its circuit opening position, and means for operating the valve to allow

of the flow of gas through the duct and for simultaneously shifting the circuit closer to its circuit-closing position, said valve actuating means being operable to release the circuit-closing mechanism, whereupon the spring operates to return the same to its normally open position.

In testimony whereof I have signed my name to this specification in the presence of two subscribing witnesses.

ROBERT HEAD.
